UNITED STATES PATENT OFFICE.

DAVID C. SWEET, OF PROVIDENCE, RHODE ISLAND.

MACHINE FOR TWISTING AND SPINNING FIBROUS MATERIALS.

No. 835,577.

Specification of Letters Patent.

Patented Nov. 13, 1906.

Application filed September 12, 1905. Serial No. 278,106.

To all whom it may concern:

Be it known that I, DAVID C. SWEET, a resident of the city of Providence, in the county of Providence and State of Rhode Island, have invented certain new and useful Improvements in Machines for Twisting and Spinning Fibrous Materials; and I do hereby declare that the following is a full, clear, and exact description thereof, reference being had to the accompanying drawings, and to the characters of reference marked thereon, which form a part of this specification.

This invention relates to spinning-rings, and has for its object the production of a simple and effective ring for increasing the capacity of the spinning-frame and is designed for application to spinning and twisting frames and the like.

My device is designed to facilitate spinning and twisting by providing an improved substitute for the fliers, rings, and travelers and the like devices heretofore employed in spinning and twisting frames and the like.

The invention consists in an improved construction of a rotating ring and whirl combined, carrying a thread-guide and supported from its internal surface on bearings both above and below the point where the driving-band engages said whirl. The bearings for this combined whirl and ring are located within an annular shell or case especially designed to inclose the same and to receive and retain any stray particles of lubricant which may have worked from the contact-surfaces.

It is a well-known fact that revolving spinning-rings on account of their high-running velocity require almost constant lubrication, which lubrication is of vital importance to the successful operation of the device. To accomplish this, many methods have been tried of submerging some of the running parts in oil and in this way pumping or forcing the oil to the bearing-surfaces; but where this is done it is found absolutely impossible in the practical operation of the ring to confine this oil so it will not be thrown upon the thread or yarn by the centrifugal force of the revolving parts and also by the generated air-pressure action upon the oil. To obviate this difficulty, I have constructed a reservoir for the reception of the lubricant, which reservoir is independent from the ring, and remove the lubricant far enough from the revolving parts, so that the centrifugal force or air-currents generated by such parts will not act on said lubricant to scatter it. I

have also arranged to draw said lubricant from the reservoir and supply it direct to the running parts in quantities just sufficient to thoroughly lubricate such parts, leaving none to be thrown off.

The invention consists of other novel features and parts and combinations of the same, as will be fully described hereinafter and then pointed out in the appended claims.

A practical embodiment of the invention is represented in the accompanying drawings, forming a part of this specification, in which similar characters of reference indicate corresponding parts in all the views.

In the drawings, Figure 1 represents my improved spinning-ring mounted on the ring-rail, which ring-rail is shown as hollowed out to serve as an oil-receptacle. Fig. 2 shows an enlarged section of a portion of the ring. Fig. 3 is a plan view of a section of the ring on line 2 2 of Fig. 1. Fig. 4 is a bottom plan view of the lower cone-bearing. Fig. 5 represents a section of the inner tube with the oil-supplying wick attached thereto and held in position on said tube by a spring-ring. Fig. 6 is a side elevation of the detachable thread-guide, showing the T-shaped slot in its periphery by which it is held on pins to the ring. Fig. 7 is a central longitudinal section of a portion of the ring-rail, which is hollowed out and serves the purpose of an oil-reservoir for supplying lubricant to the spinning-rings mounted thereon, also showing the overflow-outlet in the same. Fig. 8 is a plan view of a portion of said rail, also showing the overflow-outlet.

Referring to the drawings, 1 is the ring-rail, which I have shown as made hollow to serve as a reservoir to hold oil or other lubricant which may be supplied to the revolving rings that are mounted on said rails in the manner hereinafter described. The construction of this rail is best shown in Figs. 7 and 8, in which it is represented in the form of a trough having sides 2 2 and a bottom 3. Projecting upward at intervals from the bottom of this rail are bosses 4 4 for supporting the spinning-rings, each of which bosses has a hollow threaded center portion. At 5 is a cap or plate that covers the trough, said plate having holes 6 6 through it for the reception of the rings. At 7 in this rail is an overflow-passage for regulating the depth or the amount of oil the reservoir can hold. When the oil is poured into this rail, it rises until it reaches the bottom of this passage 7, when if

more is poured in it runs out through this opening. The object of this construction is to effectually prevent a careless operator from filling the reservoir so that the oil 5 could come in contact with or be effected by the revolving parts.

At 8 is a petcock for drawing off the oil when desired.

The rotatable spinning-ring 9 is formed 10 into an elongated annular shell or case, having a groove 10 around its middle portion for the reception of the driving-band. (Not shown.) Where the groove 10 in this ring comes, it is reinforced on its interior wall, 15 forming shoulders or bearings 11 and 12, where the balls 13 may track. The inner walls of the ring at 14 and 15, both above and below the shoulders, are beveled inwardly as they extend out from said shoulders toward 20 the ends of the ring. The object of these beveled walls is to prevent the oil from climbing up the same when the ring is revolving rapidly, the tendency being always for the oil to get as far from the center as possible. In 25 this manner the oil is retained in the pockets right where the ball finds two of its bearings. On both the upper and lower edges of this ring are shown narrow annular flanges 16 and 17, which are designed as a further prevent- 30 ive for the escape of oil; but it is found in practice that these are not necessary for this purpose. On the upper end of this ring is the thread-guide 18, which is made up in the form of a thin band inclined inwardly at 19 35 at its upper edge and has projecting from this edge a plurality of hooks or guides 20 20 to engage and carry the thread. On the lower edge of this band is a T-shaped slot 21 that sets over pins 22 22 in the upper edge of 40 the ring 9, and by a slight turn each pin enters one of the wings of the slot, and the thread-guide is securely locked in position to 45 said ring.

At 23 is a tubular portion that forms the 45 fixed inner wall and through which the bobbin is designed to pass. This tube has an outwardly-extending flange or head 24 on its upper edge, under which flange is secured the hardened, beveled, or cone-faced ring, serv- 50 ing as an upper bearing, against which the upper set of balls 13 runs. This ring may be held in place by the screws 25 25 through the flanged head of the tube 23 or in any other suitable manner. At 23^a is the check-nut, 55 that retains the said tube firmly in position in the rail.

A second hardened cone-bearing 26 is sup- 60 ported on the upper end of the bosses 4 and serves as the lower bearing for the lower set of balls 27. This ring is loosely held to the tube by the key 28 in the said tube, that enters the corresponding slot 29 in said ring. The lower portion of this tube 23 is threaded at 30 and is screwed into the boss 4 in the rail, 65 and by setting this tube either up or down the

bearings may be adjusted and the wear of the running parts taken up.

The oil is carried from the reservoir below by capillary attraction up to both the upper and lower ball-bearings through a wick 31. 70 There are various methods of holding the wick onto the side of the tube, which is preferably grooved at 33 for its reception. It may be cemented on, held in position by a spring-ring 34, as illustrated in Fig. 5 of the 75 drawings, or in any other suitable manner. This wick may be made in a half-tubular form, so that the balls may touch against its flexible edges and receive the oil therefrom; but a flat wick is used in practice with equally 80 good results. In order to carry said wick up the side of the tube, it must be passed through the slotted portion 32 in the lower cone-bearing, which slot is made in said ring for that purpose. It may then be extended up 85 through a similar slot in the upper ring and hung from the top of the same down toward the revolving balls. It will be observed that by this method the oil is applied to the balls at their innermost points, so that by centrifugal force the lubricant will spread itself all over the same in a thin film and will naturally be carried to all of its three bearing-points. As the oil is feed very slowly, not enough ever 90 accumulates to fill the pockets in the case, and no oil can possibly get out from the inside of the ring when thus constructed to 95 spoil the yarn or thread.

I have shown the rail as forming the oil-reservoir; but I do not wish to confine myself to this construction, as the reservoir may be constructed of any material and placed at any convenient point. Any reservoir that is independent and removed from the revolving parts, with means for communicating from 100 said reservoir to such parts, comes within the spirit and scope of my invention.

The above-described construction provides 105 perfect lubrication to the inclosed running parts and at the same time positively obviates the throwing of oil, which difficulty has heretofore proven fatal to the running of rotary spinning-rings at a high velocity.

This revolving ring and whirl, as stated above, runs at a great velocity. Therefore it 110 is very essential and desirable to reduce to a minimum degree the extent of the friction bearing-surface. With this end in view I have placed the supporting-bearings of the ring and whirl on the interior of said ring and as near to its center as possible, thus obtaining 115 a considerable advantage in practical construction over the old form, where the bearings are on the exterior of the ring and whirl. Another great practical advantage gained in 120 this construction over other rings of similar character is that the friction of driving the ring is reduced to a minimum by my method 125 of supporting said ring both above and below the point where the strain is applied. The 130

practical advantage of reducing the friction of the spinning-ring is obvious, as a slight reduction in the friction of each ring means a great decrease in the power required to drive the whole frame.

Having thus described my invention, what I claim as new, and desire to secure by Letters Patent, is—

1. A device of the character described comprising a rotatable spinning-ring and means for supplying lubricant to said ring by capillary attraction from an extraneous source.

2. A device of the character described comprising a rotatable spinning-ring, a reservoir, and means for automatically supplying lubricant from said reservoir to said ring by capillary attraction.

3. A device of the character described comprising a rotatable spinning-ring, a reservoir independent from said ring, and means for automatically supplying lubricant from said reservoir to said ring by capillary attraction.

4. A device of the character described comprising a rotatable spinning-ring, a reservoir independent of and removed from the revolute parts of said ring and means for supplying lubricant from said reservoir to said ring by capillary attraction.

5. A device of the character described comprising a rotatable spinning-ring, a reservoir independent and removed from the revolute parts of said ring and a wick for feeding lubricant from said reservoir to said ring.

6. In a device of the character described, a rail forming a reservoir for retaining lubricant, rotatable spinning-rings, one or more upwardly-extending portions on which the rotatable parts of said rings are supported above the lubricant, and means for feeding the lubricant to said rotating parts.

7. In a device of the character described, a rail forming a reservoir for retaining lubricant, and one or more rotatable spinning-rings mounted on said rail, and means for feeding said lubricant to said rings by capillary attraction.

8. In a device of the character described, a ring-rail forming a reservoir for retaining lubricant, one or more rotatable spinning-rings mounted on said rail and a wick for feeding said lubricant to said rings.

9. In a device of the character described, a rotatable annular case forming a whirl and the spinning-ring, a central tubular portion through which the bobbin is passed, means for adjusting said tubular portion to take up the wear of the running parts, and means for feeding oil to said running parts by capillary attraction.

10. A rotary spinning-ring comprising a rotatable annular case or shell, said shell also comprising the whirl, pockets within said

shell for retaining lubricant, a central tubular portion through which the bobbin is passed, and means for feeding lubricant to the running parts by a wick.

11. In a device of the character described, 70 a rotatable annular case forming a whirl and a spinning-ring, annular pockets having inclined walls within said case for preventing the escape of oil therefrom, a central tubular portion through which the bobbin is passed 75 and around which the case rotates, and means for taking up the wear of the parts.

12. In a device of the character described, a rotatable annular case forming a whirl and a spinning-ring, means within said case for 80 preventing the escape of oil therefrom, a central tubular portion through which the bobbin is passed and around which the case rotates, means for taking up the wear of the parts, and means including a wick for feeding 85 oil to said running parts from an extraneous source.

13. In a device of the character described, a rotatable annular case forming a whirl and a spinning-ring, means within said ring for 90 preventing the escape of oil therefrom, a central tubular portion through which the bobbin is passed, bearings fixed to said tube on which the ring rotates, and means for adjusting said tube in the rail whereby the wear of 95 the running parts is taken up.

14. A rotary spinning-ring comprising an annular case or shell, said shell also comprising a whirl, a thread-guide also carried by said case, pockets formed within said shell 100 for retaining lubricant, a central tubular portion around which the case rotates and through which the bobbin is passed, and means for taking up the wear of the running parts.

15. In a device of the character described, a rotatable annular case forming a whirl and a spinning-ring, said case also carrying a thread-guide, inclined surfaces on the interior of the case forming pockets to receive the 110 oil and prevent the same from working outward toward the edges of said case, a central tubular portion around which said case rotates and through which the bobbin is passed, and means for taking up the wear in 115 the bearings.

16. In a device of the character described, a rail forming a reservoir for retaining lubricant, rotatable spinning-rings, one or more upwardly-extending portions on which the 120 rotatable parts of said rings are supported above the lubricant, and means for feeding the lubricant to said rotating parts, and a wick for feeding said lubricant from the reservoir to the running parts.

17. A rotary spinning-ring comprising a rotatable annular case or shell, said shell also comprising the whirl, pockets within said shell for retaining lubricant, a central tubular portion through which the bobbin is 130

passed, a track-ring forming the inner bearing for each set of balls, said ring being beveled at the point of bearing, and means for feeding lubricant to the running parts by a wick.

18. In a device of the character described, a rotatable annular case forming a whirl and a spinning-ring, means within said case for preventing the escape of oil therefrom, a central tubular portion through which the bobbin is passed and around which the case rotates, a track-ring forming the inner bearing for each set of balls, said rings being beveled at the point of bearing, and means for taking up the rear of the parts.

19. In a device of the character described, a rotatable annular case forming a whirl and a spinning-ring, means within said case for preventing the escape of oil therefrom, a central tubular portion through which the bobbin is passed and around which the case rotates, means for taking up the wear of the parts, means including a wick for feeding oil to said running parts from an extraneous source, a track-ring forming the inner bearing for each set of balls, said rings being beveled at the point of bearing, and a groove or slot in said rings to receive said wick.

20. A rotary spinning-ring comprising an annular case or shell, said shell also comprising a whirl, a thread-guide also carried by said case, pockets formed within said shell for retaining lubricant, a central tubular portion around which the case rotates and through which the bobbin is passed, means for taking up the wear of the running parts, means including a wick for feeding oil to said running parts from an extraneous source, a

track-ring forming the inner bearing for each set of balls, said rings being beveled at the point of bearing, and a groove or slot in said rings to receive said wick.

21. In a device of the character described, a rotatable annular case forming a whirl and a spinning-ring, said case also carrying a thread-guide, inclined surfaces on the interior of the case forming pockets to receive the oil and prevent the same from working outward toward the edges of said case, a central tubular portion around which said case rotates and through which the bobbin is passed, means for taking up the wear in the bearings, means including a wick for feeding oil to said running parts from an extraneous source, a track-ring forming the inner bearings for each set of balls, said rings being beveled at the point of bearing, and a groove or slot in said rings to receive said wick.

22. A rotary spinning-ring comprising a rotatable annular case or shell, said shell also comprising the whirl, pockets within said shell for retaining lubricant, a central tubular portion through which the bobbin is passed, a track forming the inner bearing for each set of balls, means in said tracks whereby when they are adjusted they will take up the wear of the running parts, and means for feeding lubricant to the running parts by a wick.

In testimony whereof I have hereunto set my hand this 8th day of September, A. D. 1905.

DAVID C. SWEET.

In presence of—

HOWARD E. BARLOW,
E. I. OGDEN.
